C. A. Snow & Co.

UNITED STATES PATENT OFFICE.

JAMES M. WISHART, OF NORTH TOPEKA, KANSAS.

SAD-IRON.

SPECIFICATION forming part of Letters Patent No. 501,264, dated July 11, 1893.

Application filed July 22, 1892. Serial No. 440,901. (No model.)

To all whom it may concern:

Be it known that I, JAMES M. WISHART, a citizen of the United States, residing at North Topeka, in the county of Shawnee and State 5 of Kansas, have invented a new and useful Sad-Iron, of which the following is a specification.

This invention relates to sad irons and the object thereof is to secure improvements in 10 devices of this character which will render the same more available for the uses set forth.

With these and many other objects in view which will readily appear as the nature of the invention is better understood, the same 15 consists in the novel construction, combination and arrangement of parts hereinafter more fully described, illustrated and claimed.

In the accompanying drawings,—Figure 1 is a side elevation of a sad iron provided with 20 a heating apparatus as contemplated by this invention. Fig. 2 is a vertical longitudinal sectional view of the same. Fig. 3 is a vertical transverse sectional view on the line 3—3 of Fig. 2. Fig. 4 is an enlarged detail sectional view of the gas receiving head. Fig. 5 is a vertical longitudinal sectional view of a 25 modification. Fig. 6 is a detail perspective view partly in section, showing more clearly the connection of the heating device to the 30 hollow body.

Referring to the accompanying drawings,—A represents the hollow smoothing or flat iron having the front and rear notches *a* in the front and rear ends thereof, and the upwardly 35 extending shouldered lugs *B* at the point thereof and on both sides of the front recess at such point. An oil pipe *C* rests in the front notch or recess of said iron and is provided in front of such point with an upwardly extending 40 supporting portion *D*, which removably receives the gasoline reservoir *E*, which supplies the said pipe with the oil, and is designed to be screwed tight against the collar *b* on said pipe, which provides for a perfectly tight 45 joint. The said oil pipe *C* extends longitudinally through the hollow body *A*, and is connected at its other end within said body to the receiver head *F*. The said gas-receiver head *F* is provided at its inner end with the 50 laterally extending notched ears *f*, which rest against the inner faces of the opposite sides

of the rear notch or recess *a*, of said body and are designed to receive the securing bolts *G* passing through the end of the body to removably secure the burner within the body 55 and the gas receiver *F* in the rear notch or recess in said body thus allowing the same to be readily removed when desired. The said receiver *F* is provided with a gas reservoir or passage *H*, which leads into the outer depending passage *I*, from which passage leads the needle valve opening *J*, which is arranged directly opposite the threaded burner opening *K*, into which is removably screwed the horizontal gas burner tube *L* and extending 60 throughout the hollow body directly under the oil pipe *C*, and is provided in its under face with a series of gas escapes or openings *l*, which allow the gas escaping therefrom to be ignited and to thoroughly heat up the 65 body for the purpose for which it is adapted. The receiver *F* is further provided with the threaded neck *M* projecting outward directly opposite the needle valve opening *J* and is adapted to receive the interiorly threading 70 packing cap *M'*. The said packing cap *M'* accommodates suitable asbestos or other packing *N*, and is provided with a threaded opening *O* in the end thereof, which opening is designed to receive the threaded portion of the 75 needle valve pin *Q*. The said needle valve pin *Q* is unthreaded its entire length excepting near the outer squared end thereof as at *q*, which works in said packing cap beyond the packing therein and provides means for 80 adjusting the needle point *q'*, carried by said pin within the needle valve opening *J*. By having the needle valve pin threaded into the packing cap as described, it is rendered impossible for broken threads to be carried into 85 the valve opening, and by not working through the packing, the packing will not become cut so as to cause a leak.

The rear end of the body *A* is extended as at *R* and is provided with an integral oil cup 90 *r*, arranged directly under the open air recess *S*, between the needle valve opening *J*, and the outer open end of the burner tube into which the gas is jettisoned, and in starting the apparatus the said oil cup serves to provide 95 means for generating gas in the receiver until the burner itself, and the heat of the body 100

vaporizes the fluid as it passes through the oil pipe arranged within said body and directly over the burner tube therein.

The upper open side of the body A is in-
5 closed by the cap or cover T, which is de-
signed to fit the top of the body and have the
toe thereof engage the shouldered lugs B at
the point of the body, and is removably held
10 in position by means of the set screw t work-
ing through the rear end of the body and
against said cover, said cover being provided
with a handle U for moving the iron. If so
desired the entire gas heating apparatus may
15 be removed from the hollow body and a heated
slug V placed therein and held in position by
the cover T so as to provide ready means for
heating the body.

It is thought that the operation of the here-
in described heater is apparent without fur-
20 ther description.

Having thus described my invention, what
I claim, and desire to secure by Letters Pat-
ent, is—

In a device of the class described, the com-
bination with a hollow sad iron having end 25
notches; of the heating apparatus resting
within said notches and having a gas receiver
provided with laterally extending notched
ears, securing bolts engaging said ears and
the end of said body to removably clamp said 30
heating apparatus within the body, and a
removable cap or cover substantially as set
forth.

In testimony that I claim the foregoing as
my own I have hereto affixed my signature in 35
the presence of two witnesses.

JAMES M. WISHART.
